UNITED STATES PATENT OFFICE.

SAMUEL M. HEULINGS, OF HADDONFIELD, NEW JERSEY, ASSIGNOR TO STAR MILK COOLER COMPANY, OF HADDONFIELD, NEW JERSEY, A CORPORATION OF NEW JERSEY.

BOTTLE-LOCKING BAR.

No. 928,197.

Specification of Letters Patent. Patented July 13, 1909.

Application filed June 28, 1907. Serial No. 381,286.

To all whom it may concern:

Be it known that I, SAMUEL M. HEULINGS, of Haddonfield, in the county of Camden and State of New Jersey, have invented certain new and useful Improvements in Bottle-Locking Bars, whereof the following is a specification, reference being had to the accompanying drawings.

It is the object of my invention to prevent bottles from falling out of the case or carrier in which they are contained.

The form of my invention hereinafter described, comprises a reversible and invertible bottle locking bar having means whereby it may be detachably secured in a bottle case or carrier in such relation to the bottles as to prevent their displacement. Said bar has a series of recesses on its opposite sides, arranged to engage the necks of the bottles, and is provided with lugs at one end and a latch or bolt at the other end arranged to engage said case.

My invention includes the various novel features of construction and arrangement hereinafter more definitely specified and claimed.

In said drawings, Figure I, is a central vertical longitudinal section of a locking bar conveniently embodying my improvements, showing its application to a bottle case or carrier. Fig. II, is a plan view of said bar. Fig. III, is a transverse vertical section of said bar and the case taken on the line III, III, in Fig. I. Fig. IV, is a perspective view of the keeper plate for said bar. Fig. V, is an end elevation of the bar as seen from the left hand end with respect to Fig. II. Fig. VI, is a vertical transverse section of the bar taken on the line VI, VI, in Fig. II. Fig. VII, is an end elevational view as seen from the right hand end of Fig. II.

As shown in said figures, the bar 1, is arranged to be used in connection with a bottle case or carrier which conveniently comprises end frames 2, and 3, connected by angle edge pieces 4, and stationary bars 5. To said frames 2, and 3, are secured the keeper plates 6, each comprising the lip 8, central aperture 9, and apertures 10, conveniently disposed on each side of said aperture 9.

The locking bar 1, having the recesses 12, disposed along its opposite edges and arranged to engage the necks 13, of the bottles 14, in co-operation with the bars 5, comprises lugs 15, on one end in its median

plane, arranged to loosely enter the apertures 10, in either of the keeper plates 6, so that said bar may be lifted at its other end and withdrawn. The locking bar is thus prevented from axial rotation by the engagement of the two lugs 15, with the apertures 10. The spring bolt 18, also lying in the median plane of the bar 1, is arranged to reciprocate in the bolt recess 19, in the end of said bar to engage the aperture 9, in the other keeper plate 6. Said bolt 18, is normally shifted outwardly by the coiled spring 20, which is seated in the bolt recess 19, and which encircles the bolt stem 22, having the finger ring 23, disposed in the plane of the bar 1, within the recess 25. The throw of said bolt 18, is limited by being conveniently provided with the elongated aperture 26, arranged to embrace the pin 27, which is secured in the bolt casing 28. Said pin 27, also operates to prevent the bolt 18, from rotating, thus maintaining the finger ring 23, always in the plane of the locking bar, so that it may be easily accessible from both sides, and readily operated, no matter which face of the bar is uppermost. By locating the lugs 15, and the bolt 18, in the median plane of the bar, said bar is rendered invertible.

It may be here noted that the bottles 14, having been placed in the case or carrier, the locking bar 1, is inserted by first entering its lugs 15, in their respective apertures 10, of either of the keeper plates 6, (said plates being counterpart so that the bar is reversible,) and then pressing the bolt end of said bar into engagement with the opposite keeper plate 6, the bolt thus engages the lip 8, and is thereby retracted until it registers with the aperture 9, in which it is shot by the spring 20. To remove said bar the operator places his finger in the ring 23, and withdraws the bolt 18, from engagement with its aperture 9, which frees the bar so that it may be removed from the case.

The frame of the carrier forms the subject matter of my co-pending application for bottle carriers, Serial Number 381,284, filed June 28th, 1907. The filler for forming the compartments forms the subject matter of my co-pending application for case fillers, Serial Number 381,285, filed June 28th, 1907.

I do not desire to limit myself to the precise details of construction and arrangement herein set forth, as it is obvious that various

modifications may be made therein without departing from the essential features of my invention.

I claim:

5. 1. In a bottle case, a reversible and invertible bottle-locking bar having paired lugs on one end and a spring-pressed axial bolt on the other end; and means at both ends of the case for effecting engagement with either the 10 lugs or the bolt.
2. In a bottle case a reversible bottle-locking bar having paired lateral lugs to engage one end of said case and a spring-pressed axial bolt to engage the other end of said 15 case; and means at both ends of said case for effecting engagement with either the lugs or the bolt, said means comprising a central aperture for engaging the bolt and two lateral apertures for engaging the lugs.
20. 3. In a bottle case having stationary bars, the combination with a reversible bottle-locking bar arranged in coöperative relation with said stationary bars; of keeper plates disposed at opposite ends of said case, each 25 provided with three apertures; lugs on said locking-bars arranged to engage one or the other of said keeper plate apertures; and a bolt carried by said locking-bar arranged to engage an opposite keeper-plate aperture.
30. 4. In a bottle case having keepers disposed at its opposite ends, the combination with a reversible and invertible bottle-locking bar, having a recess near one end thereof; of lugs on the other end of said bar to engage one of said keepers; an axial bolt for engaging the 35 other of said keepers and having a finger ring accessible through said recess; and means for limiting the throw of said bolt and maintaining said ring in the plane of said bar.
5. In a bottle case having similarly apertured keeper plates disposed at its opposite ends, the combination with a reversible and invertible bottle-locking bar having a recess near one end thereof; of lugs on the other end of said bar to engage one of said keeper 40 plates; a slotted spring-pressed axial bolt carried by said bar, for engaging the other of said keeper plates and having a finger ring accessible through said recess; and a pin secured in said bar and passing through the 45 slot in said bolt for limiting the throw of the latter and maintaining said finger ring in the plane of the bar.

In testimony whereof, I have hereunto signed my name, at Philadelphia, Pennsylvania this twenty-sixth day of June 1907.

SAMUEL M. HEULINGS.
